Primary Examiner — Barbara Fox*Assistant Examiner* — Jamaal Rasheed(74) *Attorney, Agent, or Firm* — Millen, White, Zelano & Branigan, P.C.; William Nixon(57) **CLAIM**

The ornamental design for an air purifier, as shown and described.

DESCRIPTION

FIG. 1 illustrates a front perspective view of an air purifier showing our new design;

FIG. 2 illustrates a front elevational view thereof;

FIG. 3 illustrates a rear elevational view thereof;

FIG. 4 illustrates a left side elevational view thereof;

FIG. 5 illustrates a right side elevational view thereof;

FIG. 6 illustrates a top plan view thereof; and,

FIG. 7 illustrates a bottom plan view thereof.

The broken lines in the drawings depict portions of the air purifier that form no part of the claimed design.
